ELECTRICAL APPARATUS

Gustaf Einar Lofgren, Riverside, Conn., assignor
to Electrolux Corporation, Dover, Del., a cor-
poration of Delaware

Application October 1, 1940, Serial No. 359,235

5 Claims. (Cl. 171—97)

My invention relates to electrical apparatus and more particularly to household appliances of this nature.

In such devices it is often desirable to provide controls by means of which their operation may be regulated. Thus, if the device includes an electric motor, such as is used in a vacuum cleaner, it is advantageous to be able to operate the motor at different speeds. Likewise, in the case of a heating device, it is advantageous to provide means for regulating the degree of heat. From a purely electrical standpoint, this may be done by providing a multiposition switch in the circuit of the device, which may be adjusted to give the desired speed or degree of heating.

However, experience has proved that in the case of, for instance, a vacuum cleaner provided with a two-speed motor having a control switch of this nature, the device is often operated by persons having little or no knowledge of machinery and who fail to note whether the switch is positioned for high or low speed. Such persons are apt to have the switch in the low-speed position without knowing it or without realizing that the switch has two different speed positions, and become dissatisfied with the operation of the device, assuming that it is running at full speed.

This difficulty may be largely overcome if separate electric plug receptacles are provided and so connected to the current-consuming device as to produce different effects when current is supplied through the different receptacles. Thus, in a vacuum cleaner having a two-speed motor, two different plug receptacles are provided, one plainly labeled with a legend such as "high speed" and the other with a legend such as "low speed." With such an arrangement, even the least mechanically minded person will in most cases observe and notice the two receptacles and their labels and hence will be able to operate the device at the desired speed.

However, if two receptacles are provided, it is essential that there be means for opening the electrical circuit between the motor and the receptacle which is not in use, whenever a plug is connected to the other receptacle. Most receptacles of this nature in present-day use include a pair of contact prongs which, while surrounded by a shield of some sort, nevertheless may be easily touched by the hand and if these prongs were connected to a live circuit, it is obvious that there would be great danger of shock. Moreover, means should be provided for pre-

venting the connection of different plugs to two live receptacles at the same time.

In accordance with my invention, I provide such means in the form of a double-pole, double-throw switch connected in both sides of the circuits between the motor and the respective receptacles, together with means for automatically actuating this switch upon the insertion of a plug in one receptacle so as to connect this receptacle to the motor and to disconnect both prongs of the other receptacle from the motor. Moreover, the structure in accordance with my invention prevents the insertion of a plug into one receptacle whenever a plug is received in the other.

15 Further objects and advantages of my invention will be apparent from the following description, considered in connection with the accompanying drawings which form a part of this specification, and of which:

20 Fig. 1 is a view, partially in cross-section, of a vacuum cleaner embodying my invention;

Fig. 2 is a rear view of the vacuum cleaner shown in Fig. 1;

25 Fig. 3 is a cross-sectional view on an enlarged scale of a portion of the device shown in Fig. 1;

Fig. 4 is a cross-sectional view taken on the line 4—4 of Fig. 5;

Fig. 5 is a cross-sectional view taken on the line 5—5 of Fig. 3;

30 Fig. 6 is a view of a switch shown in Fig. 4, as seen from the opposite side; and

Fig. 7 is a wiring diagram.

Referring more particularly to Figs. 1 and 2, reference character 10 designates the casing of a vacuum cleaner which is adapted to be supported on a surface by means of runners 11. Suitably mounted within the casing 10 is an electric motor 12 driving a fan 13. A hose 14 is connected to one end of the casing and to a hollow handle 15 which carries a suction nozzle 16. Disposed within the casing 10 between the fan 13 and the point of communication of hose 14 is a dust-separating member 17. The opposite end of the casing is provided with an exhaust opening 18, as more clearly appears in Fig. 2.

As is well known, rotation of the fan 13 by means of the motor 12 produces a partial vacuum within the casing 10 and air is hence caused to flow through the nozzle 16, handle 15 and hose 14 to within the dust-separating member 17. If the nozzle is passed over a dusty surface, dust is entrained with this air and is carried to the dust-separating member, where it is separated from the air, the latter passing through the fan to be discharged through the exhaust 18.

It is often desirable to vary the suction effect produced at the nozzle 16, and this may be done by varying the speed of the fan 13, the motor 12 being of the two-speed type. The electrical circuit of the motor is shown in the wiring diagram of Fig. 17. As here illustrated, current may be supplied to the motor circuit through either of the terminals 20 and 21 or 22 and 23. A double-pole switch 24 is connected in the circuit of the terminals 20 and 21, while a similar switch 25 is connected in the circuit of the terminals 22 and 23. These switches are illustrated diagrammatically as being connected together by means of a mechanical connection 26 so arranged that when one switch is closed the other switch is open.

With the switch 24 closed, as shown in Fig. 7, current may flow from the terminal 20 through the switch 24 and conductor 27 and through the entire field coil 28, the armature 29, the conductor 30, switch 31, and conductor 32 to the conductor 33 which is connected to one pole of each switch. From here, the current flows through the switch 24, to the terminal 21. Under these conditions the entire field coil is energized and the motor operates at low speed. It will also be noted that, switch 25 being open, terminals 22 and 23 are both disconnected from the live motor circuit and consequently a person could contact these terminals without any danger of receiving a shock. Moreover, should the terminals 22 and 23 be connected to a source of current, this current would not be fed into the motor circuit.

If the switches 24 and 25 are placed in the opposite positions from that shown in Fig. 7, that is, with switch 25 closed and switch 24 open, and current is supplied to the terminals 22 and 23, the current will flow from the terminal 22 through the switch 25 and conductor 34 to an intermediate point of the field coil 28. From here it will continue through the lower portion of the field coil, the armature 29, conductor 30, switch 31 and conductors 32 and 33 and the other pole of the switch 25 back to the terminal 23. Inasmuch as only a portion of the field coil is energized, the motor will operate at an increased speed. Due to the fact that the switch 24 is open, the terminals 20 and 21 are dead and hence a person could not obtain a shock from contacting them.

The switch 31 is located in the motor circuit so as to make it possible to start and stop the motor, regardless of the position of the switches 24 and 25.

In Figs. 3 through 6, there is illustrated a practical embodiment in a vacuum cleaner of the circuit shown in Fig. 7. The terminals 20 and 21 are shown as prongs in a plug receptacle 36 located on one side of the vacuum cleaner, while the terminals 22 and 23 are shown as prongs of a receptacle 37 located on the opposite side.

The switches 24 and 25 are combined in a single switch structure, designated generally by reference character 40. This switch includes a chassis 41 made of insulating material and being generally U shaped, the bottom of the U constituting a curved track 42 over which are arranged to run rollers 43 and 44 made of conducting material. These rollers are connected together in axial alignment by insulating material, which is engaged by a member 45 held thereagainst by means of a spring 46. The opposite end of the spring abuts against an apertured disc 47 which loosely surrounds the upper end of

member 45 and is formed with a recess having a curved bottom. A member 48 is pivotally mounted at 49 on a bracket 50 which supports the switch and which is secured to a transverse wall 51 in the vacuum cleaner by means of bolts 52. Member 48 includes an arm 55 formed with a curved lower end which engages the curved bottom of the recess in disc 47, whereby the arm and disc may have relative pivotal movement. The above-described parts constitute a snap-action switch, the toggle arrangement holding the contact rollers 43 and 44 at one or the other of the extreme ends of the track 42 and causing them to quickly traverse the track from one end to the other whenever the member 48 is pivoted from one of its extreme positions to the other. The movement of member 48 is limited by a pair of stops 53 and 54 carried by bracket 50.

Mounted on one side of the chassis adjacent to one side of the track 42 are a pair of contacts 56 and 57. Contact 56 is connected to the prong 21 by means of a conductor 58, while conductor 27 is connected to contact 57 and leads to a terminal of the field winding 28 of the motor. Mounted on the opposite side of the chassis adjacent to this same end of the track 42 is a pair of contacts 59 and 60. Contact 59 is connected to prong 20 by means of a conductor 61, while contact 60 is connected to the switch 31 by means of the conductor 32.

Contact 60 is a part of a member which also includes a contact 62 located on the same side of the switch chassis, but adjacent to the opposite end of the track 42. The material connecting contacts 60 and 62 corresponds to conductor 33 in the wiring diagram shown in Fig. 7. Located adjacent to contact 62 is a contact 63 which is connected by means of a conductor 64 with the prong 22 of the receptacle 31. The other prong 23 in this receptacle is connected by means of a conductor 65 with a contact 66 located on the same side of the chassis as are contacts 56 and 57, but at the opposite end of the track 42. Adjacent to contact 66 is a contact 67 which is connected by means of conductor 34 with an intermediate point in the field coil 28. The switch 31 is connected to the armature of the motor through the conductor 30 which leads to one of the brushes.

The various pairs of contacts are so located that they may be bridged by either the roller 43 or the roller 44. Thus, with the switch in the position illustrated in Figs. 4 and 6, the roller 43 bridges the contacts 56 and 57, while the roller 44 bridges the contacts 59 and 60. This position of the switch corresponds to that shown in the wiring diagram of Fig. 7 and consequently current is supplied to the entire field coil and the motor operates at low speed. With the switch in the opposite position, the roller 43 would bridge the contacts 66 and 67, while the roller 44 would bridge the contacts 62 and 63 and current would be supplied to only a portion of the field coil, thus causing the motor to operate at an increased speed.

The switch is shifted from one position to the other by means of a slide structure 70 which extends through the bases of receptacles 36 and 37, where it is disposed between the prongs, as is clearly shown in Fig. 5. Structure 70 is made up of a central metallic portion 71 and end portions 72 and 73 which are preferably made of insulating material. The central portion 71 is connected to member 48 by means of a loose 75 pivot, which has sufficient play to permit mem-

ber 48 to move in an arc while member 71 moves in a straight line.

Member 70 is shifted by the insertion of an electric plug 75 into either of the receptacles 36 or 37. As shown in Figs. 4 and 5, plug 75 is inserted in receptacle 36 and member 70 has been moved to the left, as viewed in these figures. This has caused member 48 to pivot in a counterclockwise direction, as viewed in Fig. 4, and this in turn has positioned the rollers 33 and 34 so as to cause roller 43 to bridge contacts 56 and 57 and to cause roller 44 to bridge contacts 59 and 60.

Inasmuch as neither contacts 66 and 67 nor contacts 62 and 63 are bridged, prongs 22 and 23 are disconnected from the motor circuit and consequently could be touched without giving a shock. Moreover, if the prongs 22 and 23 were to be connected to a source of electricity by means of another plug, the current would not be conveyed to the motor circuit. However, due to the fact that portion 73 of the member 70 extends a substantial distance into receptacle 37, it would be impossible to insert a plug in this receptacle unless sufficient force were applied to dislodge the plug 75 from the receptacle 36.

In the event it is desired to operate the motor at maximum speed, the plug 75 is removed from the receptacle 36 and placed in the receptacle 37. The insertion of the plug in this latter receptacle displaces the member 73 to the right, as viewed in Figs. 4 and 5, and this in turn shifts the switch to a position in which roller 43 bridges contacts 66 and 67 and roller 44 bridges contacts 62 and 63. Thus current is supplied to an intermediate point of the field winding and the motor runs at maximum speed. Due to the fact that neither contacts 66 and 67 nor contacts 59 and 60 are bridged, the prongs 20 and 21 are disconnected from the motor circuit.

There is thus provided an arrangement which reduces to a minimum the possibility of confusion with respect to the speed at which the motor is operating, and which at the same time is absolutely safe and foolproof. While I have shown my invention as being used in connection with a vacuum cleaner, it is obvious that it may be employed with advantage in any electrical device, and the scope of my invention is not to be limited by the embodiment described for purposes of illustration, but is to be determined by the appended claims.

What I claim is:

1. In an electrical device, a plurality of plug-receiving members, electric conductors providing a circuit connected to each of said members, and means actuated by the connection of a plug to any one of said members for opening the circuit to which the remainder of said members is connected.
2. In an electrical device, a plurality of separate and independent plug-receiving members, and means actuated by the connection of a plug to any one of said members for preventing the connection of another plug to the remainder of said members.
3. In an electrical device, a plurality of plug-receiving receptacles, a pair of electric conductors connected to each receptacle, an electric switch in each of said conductors, and means actuated by the connection of a plug to any one of said receptacles for closing the switches in the pair of conductors connected to that receptacle and for opening the remainder of said switches.
4. In an electrical device, a pair of plug-receiving receptacles, a pair of electric conductors connected to each receptacle, an electric switch in each of said conductors, and movable structure having portions disposed in said receptacles and adapted to be moved by the insertion of a plug into either of the receptacles for shifting said switches, so as to close the switches in the conductors connected to the receptacle into which the plug is inserted and to open the other switches.
5. In an electrical device, a pair of oppositely disposed plug-receiving receptacles, a pair of electric conductors connected to each receptacle, switch structure disposed between said receptacles, said structure including an electric switch in each of said conductors having movable contact making and breaking means, and movable structure extendable into either of said receptacles and adapted, by the insertion of a plug into that receptacle in which said movable structure is extending, to be moved so as to extend into the other receptacle, said contact-making and breaking means being operatively connected to said movable structure so as to close the switches in the conductor connected to the receptacle into which the plug is inserted and to open the other switches.

GUSTAF EINAR LOFGREN.
